UNITED STATES PATENT OFFICE.

RICHARD ERNEST, OF NEW YORK, N. Y.

PLASTIC HAIR WORK AND METHOD OF CONSTRUCTING SAME.

Application filed February 13, 1922. Serial No. 536,140.

To all whom it may concern:

Be it known that I, RICHARD ERNEST, a citizen of the United States, and resident of New York, in the county of New York and State of New York, have invented a certain new and useful Plastic Hair Work and Method of Constructing Same, of which the following is a specification.

The principal object of this invention is to provide a new means for concealing baldness which will defy detection and will therefore overcome the known disadvantages of and supplant the use of wigs.

A further object is to provide a plastic foundation which can be accurately moulded to fit the shape of the bald part of any individual head.

Another object is to provide an artificial covering for baldness comprising a plastic background in which human hair is inserted, the hairs being placed in the plastic singly and not in groups thereby imitating nature with great fidelity.

Another object is to provide a background for the hair which can be made to present an exactly similar appearance to the human scalp and which can readily be tinted or colored to coincide with the complexion of the individual, and a further object is to provide a method for the construction of the finished plastic hairwork product.

For the accomplishment of these and such further objects as will be hereinafter apparent to those skilled in the art to which this appertains, the invention consists in the construction, combination and arrangement of parts or materials and the method of producing or assembling them herein specifically described and illustrated in the accompanying drawings wherein is diagrammatically shown a preferred embodiment of a method and construction of the invention but it is to be understood that changes, variations and modifications may be resorted to which fall within the scope of the claims hereunto appended.

In the drawings forming a portion of this specification

Fig. 1 is a side view of a mould showing the first stage of a preferred method of carrying out my invention.

Fig. 2 is a similar view showing a more advanced stage of the method.

Fig. 3 is a side view of a completed head covering for a case of complete baldness.

Fig. 4 is a sectional view showing the construction of a completed plastic hairwork.

Fig. 5 is a section showing diagrammatically the manner in which the single hairs are inserted into the plastic and the condition of the plastic before being heated, and

Fig. 6 is a similar view showing the manner in which the plastic flows around and grips the hairs after being heated.

In carrying out my invention I first take a mould of the outline of the head to be treated for baldness whether complete baldness, partial baldness or baldness of the top portion only, the mould being preferably of plaster of paris or any other suitable material. After this mould has set and hardened another working mould of similar material is then cast therefrom giving an accurate reproduction of the outline of the bald portion of the head to be treated, with all depressions and contours faithfully reproduced.

Upon this working mould as shown in Fig. 1 a coating of rubber solution is then placed according to the size of the baldness to be covered, the larger outline indicated by the letter A in Fig. 1 showing the outline for covering complete baldness, the dot and dash line B indicating partial baldness, and the dot and dash line C indicating top baldness. The dotted line D represents a somewhat exaggerated showing of a depression such as sometimes occurs in the outline or contour of the head of various individuals, in which cases it is possible for me to place a piece of padding or filling beneath the plastic to correct such irregularities.

After having coated the mould with the rubber solution, a layer of silk fibre F is placed over the solution and for convenience in working is preferably extended and secured to the mould approximately one inch beyond the outline of the foundation desired, this silk fibre forming the background of the finished plastic and serving as a base or body to receive and hold the upper layer of the plastic. If the plastic is to be made for a case of entire baldness a small V-shaped piece of elastic material G is inserted in the inward curve behind the ears for the purpose of allowing the plastic to be readily placed on or taken off the head. A silk fibre thread H is then placed upon the silk fibre extending around and parallel to the final outline of the foundation a short dis-

tance from the edge thereof. The purpose of this silk thread is to hold the plastic in the proper concaved shape and prevent it from opening or straightening out when removed from the mould.

A mixture of gelatine and glycerine is then prepared and the silk fibre is coated with this mixture to which any suitable coloring or pigments are added to secure the 10 desired tint or color to simulate the appearance of the human scalp, proper amount and character of the coloring depending upon the color desired according to the complexion of the individual for whom the hair-work is being made. As many coatings of this mixture will be applied as is necessary to obtain the required thickness.

Into this plastic foundation J single hairs K are then inserted with any suitable sharp 20 needle like instrument, only one hair being inserted at each spot and the hairs being worked into the plastic from the edges towards the crown, it being understood that the hairs are inserted at an inclination as 25 shown in the drawings, the inclination of the exposed portion of the hair being away from the crown. The hair is inserted into the foundation a sufficient distance to project slightly beyond the inner side for a purpose which will hereinafter appear.

The foundation is then removed from the mould and cut out along the original lines of measurement after which the outer side in which the hairs are implanted is treated 35 with a solution of formaldehyde which renders the upper layer light and insoluble after it has dried.

The inner surface of the foundation is now given a coating of gum and collodion 40 which not only acts to hold the projecting inner ends of the hairs securely in the plastic but also serves to make the inner side of the plastic slightly adhesive so that it will stick securely to the head when placed 45 thereon.

After the final inner coating has been applied, the plastic hair-work is then heated to a moderate temperature until both the outer and inner layers become slightly viscous. 50 The outer layer thereby flows around and tightly grips each single hair as shown in Fig. 6 while the inner layer of gum and collodion also adheres strongly to the inner projecting ends.

It is desirable to pierce the foundation through with a plurality of small holes or pores L which provide for ventilation.

It will be understood that any length of hair may be used according to the wishes of 60 the individual or whether the hair-work is to be used for men or women.

Having thus disclosed my invention what I claim as new and desire to secure by Letters Patent of the United States, is:—

65 1. An artificial hair covering for the hu-

man head made to present a perfect resemblance to the natural human scalp and hair comprising a plastic outer layer, an adhesive plastic inner layer, a fibre base intermediate said plastic layers and a plurality of hairs imbedded in and through said layers and base. 70

2. An artificial hair covering for the human head made to present a perfect resemblance to the natural human scalp and hair comprising a plastic foundation having an elastic piece inserted therein to permit said foundation to be expanded or contracted. 75

3. An artificial hair covering for the human head made to present a perfect resemblance to the natural human scalp and hair comprising a plastic foundation, hairs imbedded therein and a silk fibre thread imbedded in said foundation adjacent its outer outline, whereby the foundation will be retained in a curved concave form. 80

4. In an artificial hair covering for the human head made to present a perfect resemblance to the natural human scalp and hair, a foundation comprising a plastic outer layer, an adhesive plastic inner layer, a fibre base intermediate said plastic layers, a silk fibre thread adjacent the edge of said foundation and a plurality of hairs imbedded in said foundation. 90

5. In an artificial hair covering for the human head made to present a perfect resemblance to the natural human scalp and hair, a foundation comprising a plastic outer layer, an adhesive plastic inner layer, a fibre base intermediate said plastic layers, a silk fibre thread adjacent the edge of said foundation and a plurality of single hairs separately imbedded in said foundation. 100

6. An artificial hair covering for the human head made to present a perfect resemblance to the natural human scalp and hair comprising a plastic foundation in which the hairs are imbedded and said foundation having a plurality of holes therethrough to provide ventilation. 105

7. In an artificial hair covering for the human head made to present a perfect resemblance to the natural human scalp and hair, a plastic foundation shaped to conform to the human head comprised of gelatine and glycerine. 115

8. In an artificial hair covering for the human head made to present a perfect resemblance to the natural human scalp and hair, a plastic foundation comprising an outer plastic layer of gelatine and glycerine, an inner plastic layer of gum and collodion, a fibre base intermediate said layers and a plurality of hairs imbedded in said foundation. 120

9. The method of constructing an artificial hair covering which consists in taking a mould of the part to be covered, making a working mould from said first mentioned mould, applying a coating of rubber solu-

tion to said working mould, applying a piece of silk fibre on said rubber coating, applying successive layers of plastic composition to said silk fibre, whereby a plastic foundation 5 is secured, inserting a plurality of single hairs into said plastic foundation at separated points thereof, applying formaldehyde to the outer side of said foundation, removing said foundation from said mould, applying 10 an adhesive plastic composition to the inner side of said foundation and finally heating said covering to agglomerate said plastic compositions.

10. The method of constructing an artificial hair covering which consists in taking a mould of the part to be covered, making a working mould from said first mentioned mould, applying a coating of rubber solution

to said working mould, covering said solution with a piece of silk fibre, applying successive layers of a plastic composition composed of gum and gelatine to said fibre whereby a plastic foundation is formed, inserting a plurality of single hairs at separated points in said foundation, applying formaldehyde to said plastic composition, removing said foundation from said working mould, applying a coating of adhesive plastic composition consisting of gum and collodion to the inner side of said foundation, and finally heating said covering to agglomerate 20 25 30 said plastic compositions.

Signed at New York, in the county of New York, and State of New York this 19th day of January A. D. 1922.

RICHARD ERNEST.
